UNITED STATES PATENT OFFICE

LEONARD D. SOUBIER, OF TOLEDO, OHIO, ASSIGNOR TO OWENS-ILLINOIS GLASS COMPANY, A CORPORATION OF OHIO

GLASSWARE FORMING MACHINE

Application filed March 26, 1930. Serial No. 438,941.

The present invention relates to improvements in glassware forming machines and particularly to machines in which articles of glassware are partially formed in molds on one table and then transferred to finishing molds mounted on a support separate from said table, for final shaping.

An object of the present invention is the provision of an improved machine of the above character, wherein the finishing molds are mounted on an endless chain or the like carrier which moves the finishing molds in succession past blank transfer, blowing and discharge stations. To this end, an endless chain is arranged to move in a horizontal plane in timed relation to movements of an annular series of blank forming units disposed in proximity to and brought in succession to the blank transfer station. Both the endless chain carrying the finishing molds and the blank forming units move continuously, thereby providing for maximum production of glassware and reduction of wear and strain on the operating mechanism.

Another object is the provision in a machine of the above character, of novel means for transferring blanks from blank forming units to finishing mold units in which the molds are mounted on an endless chain or similar carrier. To this end the blank forming units include neck molds adapted to move into position over and in register with the finishing molds and travel therewith a sufficient distance to allow transfer of blanks or parisons suspended from the neck molds, to the finishing molds, without distortion.

Other objects will be apparent hereinafter. In the drawings:

Fig. 1 is a plan view diagrammatically illustrating my invention.

Fig. 2 is a vertical sectional elevation showing the blank mold and finishing mold at the blank transfer station.

Fig. 3 is a plan view showing one of the blank mold tables and a portion of the finishing mold unit.

Fig. 4 is a fragmentary sectional view taken substantially along the line IV—IV of Fig. 5.

Fig. 5 is a fragmentary plan view of one end of the finishing mold unit.

Fig. 6 is a front elevation of one of the finishing mold groups or heads.

Fig. 7 is a sectional elevation taken along 55 the line VII—VII of Fig. 6.

Fig. 8 is a detail sectional view showing the valve mechanism for controlling the supply of air under pressure.

Fig. 9 is a vertical sectional view of one of 60 the blowing heads which co-operates with the finishing molds in expanding the blanks or parisons.

In more or less general terms, the illustrated embodiment of my invention includes 65 an annular series of blank forming units rotating continuously about a vertical axis past charge gathering and blank transfer stations. Each unit comprises a partible body blank mold and a partible neck mold, preferably, but not necessarily, of the type employing suction or vacuum in obtaining mold charges from a supply body of molten glass. Any conventional or preferred means may be employed to operate these molds and other mechanism associated therewith, so that said molds gather charges of molten glass at the charging station and then transfer the glass, in the form of blanks or parisons, to partible finishing molds at said transfer station. The 70 finishing molds are mounted on an endless chain trained over a pair of horizontally spaced sprockets and moving continuously in a substantially horizontal plane.

The blank transfer station is arranged adjacent one sprocket and the article discharging station in proximity to the other sprocket. Accordingly, blanks are placed in the finishing molds at the transfer station, and while traveling to the discharging station are expanded to their final shapes. The finishing molds then open and eject the finished articles.

More specifically, the machine comprises an annular series of blank forming units 15 95 rotatable continuously about a vertical axis past mold charging and blank transfer stations "G" and "T" respectively. These blank forming units 15, each comprising a partible body blank mold 16 and a cooperating neck 100

mold 17, are mounted on a rotary mold carriage 18 suitably supported on a stationary central column 19, the latter rising vertically from a base 20. Each body blank mold 16 (Fig. 2) is connected to the mold carriage 18 through a bell crank lever 21 which is fulcrumed upon a horizontal hinge pin 22. One arm of the bell crank lever carries a cam roll 23 which moves over stationary cams 24 shaped to rock the bell crank lever at regular time intervals. Such rocking of the bell crank lever alternately raises and lowers the body blank mold 16 so that it may clear the rim of the furnace extension 25 (Fig. 3), dip 15 into the molten glass in said furnace extension to gather mold charges and then, following the charging operation, resume an upright position in advance of arrival at the blank transfer station "T". The body blank 20 mold 16 is alternately opened and closed by a stationary cam 26 operating through a slide 27 and arms 28 which are suitably connected to the slide, said arms supporting the body blank mold sections. These arms are 25 pivoted to vertical hinge pins 28^a on the bell crank lever 21. The neck mold 17 is mounted for radial movement relative to the corresponding body blank mold 16, primarily for the purpose of carrying blanks or parisons 30 to a position radially outward from said body blank mold at the transfer station "T". Such projection of the neck mold 17 forms an important part of the blank transfer operation, as will be apparent hereinafter. The 35 neck mold is connected through arms 31 and a hinge pin 32 to a neck mold carrier 29 (Fig. 2), which is slidably supported on a pair of guide rods 30 extending radially of the horizontal arm of the bell crank lever 21. 40 Radial reciprocation of the neck mold carrier 29 for the purpose of alternately placing the neck mold in register with the body blank and finishing molds is obtained by a stationary cam 33 (Figs. 2 and 3) in which runs 45 a cam roll 34 suitably mounted on the upper side of the neck mold carrier 29. The cam 33 (Fig. 3) is provided with a re-entrant section 35 at the blank transfer station "T", which causes the neck molds 17 to travel along a straight path at said station in register with the latter during the blank transfer operation.

Each neck mold 17 is opened at regular time intervals by mechanism including a 50 wedge 36 mounted on the lower end of a holder 37 and adapted to be projected downwardly between the neck mold arms 31 at times. This wedge 36 spreads the arms 31, and, as a result, opens the neck mold 17. A spring device (not shown) yieldingly holds the neck mold closed. Such downward movement of the holder 37 and wedge 36 is obtained by a cam actuated rocker arm 38 pivoted on a bracket 39 mounted on the neck mold carrier 55 29, said rocker arm being swung downward-

ly at regular time intervals by means of a stationary cam 40 suitably supported on the neck mold projecting cam 33. This cam 40 is so positioned that it moves the arm 38 downwardly approximately at the time the 70 finishing molds completely close at the transfer station "T". Thus, the neck mold 17 positively supports the blanks during closing of the finishing molds. A spring (not shown) lifts the wedge and holder 37 to their uppermost positions after the transfer operation, thereby allowing the neck mold to snap closed. Any preferred means (not shown) may be employed to supply vacuum and air under pressure to the body blank and neck 80 molds for the purpose of gathering mold charges and compacting mold charges, respectively, in the molds. Additional information relative to the particular type of blank forming units illustrated in this application and described above may be had by referring to British patent to O'Neill, 315,- 85 154, dated July 11, 1929.

Finishing mold units 45 in the illustrated embodiment of this machine are mounted upon an endless chain 46 trained over a pair of horizontally spaced sprockets 47 suitably supported at the upper ends of vertical shafts 48. These shafts are arranged at opposite ends of an elongated finishing mold carriage and journaled in a series of vertically spaced bearings, including a lower bearing 49 carried by the base plate 20, intermediate bearings 50 formed on a central frame 51 and upper bearings 52 carried by a top frame 53. Continuous rotary movement is imparted to the endless chain 46 through the provision of driving connection between the rotary blank mold carriage 18 and one of said vertical shafts 48. This driving connection (Fig. 2) consists of a ring gear 54 on the blank mold carriage 18 driving a pinion 55 fixed to the upper end of a vertical shaft 56. Gears 57 and a horizontal shaft 58 provide connection between the shafts 56 and 48. The drive is 100 such that the blank forming units 15 and finishing mold units 45 are moved in substantially the same direction at the transfer station "T" as, and for the purpose stated herefore. 105

The central frame member 51 of the finishing mold carriage (Figs. 2, 4, 6 and 7) is supported on brackets 59 or legs secured to the upper side of the base 20. A continuous bearing plate 60 extends about the margin of the central frame member 51 of the finishing mold carriage and is adapted to slidably support the series of finishing mold carriers 61 which are individual to the finishing mold units 45. Immediately beneath this bearing plate is 110 formed an air pressure chamber 62 extending parallel with the bearing plate along one side of the finishing mold carriage and lying in its entirety between the transfer station "T" and the article ejecting station "D" (Fig. 1). Air 115 120 125 130

under pressure is constantly supplied to the chamber 62 by a supply pipe 63 which is connected to any suitable source of supply (not shown). A cam 64 (Figs. 2 and 7) is attached to said central frame member 51, and, as will be apparent hereinafter, controls the vertical positions of the finishing mold bottom plates to be described. A cam 65 (Fig. 8) is mounted on the central frame member 51 just above the bearing plate 60 to actuate valve mechanism which controls operation of blowing heads for the finishing molds, as will be set forth presently. The top frame 53 of the finishing mold carriage supports upper and lower cams 66 and 67, the lower, or finishing mold operating cam 67, being shaped to close the finishing molds at the transfer station "T" and open them just in advance of arrival at the article discharging station "D", while the upper or blowing head control cam 66 alternately projects and retracts the blowing heads in timed relation to movements of the finishing molds.

Each finishing mold unit 45 (Figs. 2 and 4) includes a partible finishing mold 68 connected through mold arms 69 to a vertical hinge pin 70 rising from the base 71 of the finishing mold carrier 61. This finishing mold carrier is connected through a yoke 72 and vertical hinge pin 73 to the endless sprocket chain 46. A roller 74 mounted on the lower end of the hinge pin 73 constantly rides upon a track 75, or bearing plate, cooperating with an adjacent part 74a in preventing horizontal movement of the finishing mold carrier 61 in a direction transverse to the normal path of travel. Alternate opening and closing of the finishing mold 68 is obtained by means including a slide 76 mounted in slideways or guides 77 formed on the adjacent faces of upstanding arms 78 which are carried by the base 71 and comprise part of the finishing mold carrier. This slide 76 is connected at one end through links 79 to the finishing mold arms 69, and at its other end carries a cam roll 80 running in the cam 67. This cam 67 (Figs. 3 and 5) is provided with an angular portion 81, at the transfer station "T" (Fig. 3), which moves the slide 76 outwardly during substantially the first half of the transfer period, thereby closing the finishing mold about a blank while it is still positively supported by a neck mold 17. This cam 67 need, and in fact does, extend only a short distance beyond the transfer station "T", because the corresponding blowing head, to be described presently, functions to positively hold the finishing mold closed during the blowing operation. Adjacent to and a short distance in advance of the article ejecting station "D", the cam 67 is provided with an angular portion 82 (Fig. 5) which reverses the movement of the finishing mold opening and closing slide 76 so that the finishing mold 68 is opened, leaving the

finished article standing upright on the bottom plate ready to be ejected at said station.

A bottom plate 83 (Fig. 4) is provided for each finishing mold 68 to close the lower end of the mold and shape the bottoms of the articles of glassware. This bottom plate includes a holder 84 in which the bottom plate is adjustably supported. The holder 84 (Fig. 4) is pivoted to a horizontal hinge pin 85 on a bracket 86 which is carried by the base 71 of the finishing mold carrier, said holder being operatively connected to a rocker arm 87 by a coil spring 88. This rocker arm 87 carries a cam roll 89 which at proper times rides over the stationary cam 64 referred to heretofore. This cam 64 (Figs. 3, 5 and 7) is so shaped that it raises the bottom plate 83 into operative position relative to the corresponding finishing mold just prior to closing of the latter at the transfer station "T" and allows said bottom plate to tilt at the article ejecting station "D" for the purpose of discharging the finished articles.

After a blank has been transferred to a finishing mold 68 at the station "T" and the finishing mold completely closed about the blank, a blowing head 90 is brought into operative position relative to the finishing mold, primarily for the purpose of introducing air under pressure into the finishing mold to expand the blank to its final shape and secondarily, to positively hold the finishing mold closed during the final blowing operation. The blowing head 90 comprises a piston motor 91 mounted on the outer end of a slide 92 which is slidingly supported in guideways 93 just above the finishing mold opening slide 76. A cam roll 94 at the inner end of the blowing head slide 92 runs in the cam 66 (Figs. 2 and 5), said cam shaped to alternately project and retract the blowing head at regular time intervals. A differential piston motor 95 is mounted in the cylinder of the piston motor 91 and carries a sleeve 96 which projects through the lower open end of said cylinder. The lower end of the sleeve 96 (Fig. 9) is formed with a beveled surface 97 adapted to contact with a similar surface comprising one wall of a channel 98 in the upper end of the corresponding finishing mold 68. Downward projection of the sleeve 96 into engagement with the finishing mold, so that said beveled surfaces contact with each other, positively holds the finishing mold 68 against premature opening under pressure of blowing air employed in expanding the articles to their final shape.

Means for alternately raising and lowering the sleeve 96 and regulating the supply of air under pressure through said sleeve into the corresponding finishing mold includes a pipe 99 communicating by way of a port 100, with the piston motor cylinder at a point below the differential piston 95. The other end of the pipe 99 communicates 130

by way of a passageway 101 (Figs. 4 and 8) in the base 71 of the finishing mold carrier 61 with the chamber 62 which contains a supply of air under pressure. Thus, air under pressure is constantly applied to the lower side of the differential piston 95 and normally holds the latter in its uppermost position whereby the sleeve 96 is almost completely enclosed within the piston motor cylinder. Accordingly, the sleeve does not interfere with horizontal movement of the blowing head relative to the finishing mold. Air under pressure is introduced into the upper end of the piston motor cylinder at regular time intervals to move the differential piston 95 downwardly and cause engagement between the sleeve 96 and the corresponding finishing mold. Such movement of the sleeve also in part controls the application of blowing air to the interior of the finishing mold, as will be apparent presently. A supply pipe 102 (Figs. 4, 6, 7, 8 and 9) opens at one end into the upper end of the piston motor cylinder and at its other end into a chamber 103 of a valve box 104. This chamber 103 communicates with the passageway 101 containing air under pressure by way of a valved opening in one wall of said chamber. A valve 105 on a valve rod 115 (Fig. 8) normally closes said opening under influence of a coil spring 106 encircling said rod. The cam 65 referred to heretofore engages a cam roll 107 on the rod 115 at regular time intervals to unseat the valve 105 and thereby admit air under pressure to the pipe 102 and thence to the upper end of the cylinder of the piston motor 91. Thus, the differential piston 95 is moved downwardly, causing the sleeve 96 to seat upon the corresponding finishing mold 68. Such downward movement of the piston 95 causes alignment of a port 108 in the sleeve with a port 109 in the lower end of the piston motor cylinder, resulting in flow of air under pressure into the sleeve by way of said ports from a pipe 110. This pipe 110 is suitably connected to the pipe 102 which leads to the chamber 103, as described above. Release of pressure in the upper end of the piston motor cylinder after each final blowing operation, so that the differential piston 95 may be lifted under pressure of air flowing through the pipe 99, is obtained by means of a relief pipe 111, one end of which communicates with the interior of the cylinder near the upper end of the latter, while its other end opens into a chamber 112 in the valve box 104. This chamber 112 has a valved opening in one wall, which at times is closed by valve 113 and at other times operates with ports 114 (Fig. 8) in providing communication between the relief pipe 111 and the atmosphere. The valves 105 and 113 are mounted on said valve rod 115 which carries the cam roll 107 referred to heretofore. Thus the valves open and close in al-

ternation under the influence of the spring 106 and cam 65 and in this manner cause vertical reciprocation of the differential piston motor 95, periodically.

In operation, the blank forming units 15 and finishing mold units 45 (Fig. 3) are moved continuously in the directions indicated by the arrows so that at the blank transfer station "T", the units move in substantially the same direction. The re-entrant section 35 of the cam 33 controlling the radial position of the neck molds 17 at the blank transfer station "T" insures accurate vertical alignment of the neck and finishing molds during the blank transfer operation so that the blanks are not in the least distorted or marred. The blanks are positively held by the neck molds during approximately the first half of the transfer operation and while so held are enclosed by the finishing molds 68 due to outward movement of the finishing mold closing slides 76 under influence of the angular portion 81 of the cam 67. During the latter half of the blank transfer operation, the neck molds 17 open, completely releasing the blanks to the finishing molds which move in a straight line toward the article ejecting station "D". Shortly after passing the blank transfer station "T", an angular portion 66^a in the blowing head control cam 66 projects the blowing head 90 (Figs. 4 and 6) to a position over and in register with the corresponding finishing mold. Air under pressure is then introduced into the upper end of the piston motor 91 through the pipe 102 so that the sleeve 96 is lowered into engagement with the upper end of the corresponding finishing mold. The valve 105 is then opened by means of the cam 65 and air under pressure directed into the finishing mold through the pipe 110 and aligned ports 108 and 109, causing final expansion of the article of glassware. This final expansion of the article is followed by lifting of the blowing sleeve 96 and retraction of the entire blowing head 90 to a position spaced inwardly from the finishing mold. The finishing mold is now opened by means of the cam 67 operating through the slide 76, thereby leaving the finished article in an upright position on the bottom plate 83. At the article discharging station "D", an angular portion 64^a of the cam 64 allows the bottom plate 83 to tilt and thereby eject the finished article into a chute or other receiver (not shown). The finishing molds are held open until they return to the blank transfer station "T" where they again enclose the blanks or partially formed articles of glassware and the operation above described is repeated. While the finishing molds are open, they will of course be cooled and thereby be properly conditioned to receive other blanks for final expansion.

Modifications may be resorted to within

the spirit and scope of the appended claims.

What I claim is:

1. In a glassware forming machine, the combination of a series of finishing molds moving in a closed horizontal path past a blank transferring position, means for placing blanks in the finishing molds at said positions, supporting means for the finishing molds including a continuous upwardly facing bearing plate 10 extending parallel with the path of travel of the finishing molds, carriers individual to the finishing molds slidingly supported on said plate, means for continuously moving the carriers and finishing molds over said bearing plate, means including blowing heads individual to the finishing molds for expanding the blanks in the latter, means for supplying air under pressure to the blowing heads periodically, valve individual to the finishing molds for controlling flow of air under pressure to the blowing heads, and a cam carried by the bearing plate for actuating the valves in succession.

2. In a glassware forming machine, the combination of a series of finishing molds moving in a closed horizontal path past a blank transferring position, means for placing blanks in the finishing molds at said position, supporting means for the finishing molds including a continuous upwardly facing bearing plate extending parallel with the path of travel of the finishing molds, carriers individual to the finishing molds slidingly supported on said plate, an endless chain connecting the series of finishing mold carriers, and means for continuously moving the chain to thereby cause the finishing molds to travel in succession past said transfer position.

3. In a glassware forming machine, a series of partible finishing molds arranged for continuous movement in a horizontal path, a major portion of which extends along two parallel straight lines, a continuous bearing plate supporting the molds, a tiltable bottom plate for each mold, a blowing head arranged in a plane above and individual to each mold, and operating means individual to the mold bottom plate and blowing head for operating them in a predetermined order.

4. In a glassware forming machine, a series of finishing mold units movable in a closed horizontal path, a major portion of which extends along two parallel straight lines, a continuous bearing plate supporting said units, each unit comprising a non-tilting partible mold, a tiltable bottom plate for the mold, a blowing head individual to the mold, and operating mechanism individual to the mold, bottom plate, and blowing head, for operating them in a predetermined order.

5. In a glassware forming machine, a series of finishing mold units movable in a

closed horizontal path, a major portion of which extends along two parallel straight lines, a continuous bearing plate supporting said units, each unit comprising a non-tilting partible mold, a tiltable bottom plate for the mold, a blowing head individual to the mold, means for moving the units in succession past blank transferring, blowing and discharging positions, means for closing the mold about a blank at the blank transferring position, means for projecting the blowing head and causing operative positioning thereof with respect to the mold at said blowing position, and means for opening the mold and tilting the bottom plate at the discharging position.

6. In a glassware forming machine, a series of finishing mold units movable in a closed horizontal path, a major portion of which extends along two parallel straight lines, a continuous bearing plate supporting said units, each unit comprising a non-tilting partible mold, a tiltable bottom plate for the mold, a blowing head individual to the mold, means for moving the units in succession past blank transferring, blowing, and discharging positions, means for closing the mold about a blank at the blank transferring position, means for projecting the blowing head and causing operative positioning thereof with respect to the mold at said blowing position, and means for opening the mold and tilting the bottom plate at the discharging position, said means for operating the mold, blowing head, and bottom plate including a series of superposed stationary cams.

7. In a glassware forming machine, a series of finishing mold units movable along a closed path, a major portion of which extends along two parallel straight lines past blank transferring, blowing, and article discharging positions, a continuous bearing plate supporting said units, a chamber provided in said bearing plate to contain a supply of air under pressure, each finishing mold unit comprising a carrier slidingly supported on said plate, a finishing mold on said carrier, a tilting bottom plate individual to the mold and supported on the carrier, a blowing head on the carrier, and means including an automatically controlled valve for conducting air under pressure from said chamber to the blowing head.

8. In a glassware forming machine, a series of finishing mold units movable along a closed path, a major portion of which extends along two parallel straight lines past blank transferring, blowing, and article discharging positions, a continuous bearing plate supporting said units, a chamber provided in said bearing plate to contain a supply of air under pressure, each finishing mold unit comprising a carrier slidingly supported on said plate, a finishing mold on said

- carrier, a tilting bottom plate individual to the mold and supported on the carrier, a blowing head on the carrier, means including an automatically controlled valve for 5 conducting air under pressure from said chamber to the blowing head, and cam actuated devices individual to the mold, bottom plate, and blowing head for operatively positioning them in a predetermined order.
- 10 9. In a glassware forming machine, a series of finishing mold units movable along a closed path, a major portion of which extends along two parallel straight lines past blank transferring, blowing, and article dis- 15 charging positions, a continuous bearing plate supporting said units, a chamber provided in said bearing plate to contain a supply of air under pressure, each finishing mold unit comprising a carrier slidingly support- 20 ed on said plate, a finishing mold on said carrier, a tilting bottom plate individual to the mold and supported on the carrier, a blowing head on the carrier, a valve cham- 25 ber provided in said carrier and communi- cating at regular time intervals with said air chamber, conduits connecting the valve chamber and blowing head, and a cam actuated valve in said valve chamber operable at regular time intervals to establish communi- 30 cation between said air chamber and conduits.
10. In a glassware forming machine, a series of partible finishing molds arranged for movement along a closed horizontal path 35 a major portion of which is non-circular, a continuous bearing plate supporting the molds, a tiltable bottom plate for each mold, a blowing head arranged in a plane above the molds, and means for operating the blow- 40 ing head and bottom plate in a predeter- mined order.
11. In a glassware forming machine, a series of finishing mold units movable in a closed horizontal path a major portion of 45 which is non-circular, means providing a continuous bearing surface supporting said units, each unit including non-tilting partible molds, a tiltable bottom plate for each mold, a blowing head, means for moving the 50 units in succession past blank transferring, blowing and discharging positions, means for enclosing a blank in a finishing mold unit at the blank transferring position, means for operatively positioning the blowing head at 55 the blowing position, and means for opening the mold and tilting the bottom plate at the discharging position.

Signed at Toledo, Ohio, this 21 day of March 1930.

LEONARD D. SOUBIER.
